UNITED STATES PATENT OFFICE.

GEORGE W. BUSCH. OF FLORENCE, MASSACHUSETTS.

OIL-BURNER.

Specification of Letters Patent. Patented Sept. 19, 1911.

1,003,700.

Application filed September 27, 1910. Serial No. 584,005.

To all whom it may concern:

Be it known that I, GEORGE W. BUSCH, a citizen of the United States of America, residing at Florence, in the county of Hampshire and State of Massachusetts, have invented a new and useful Oil-Burner, of which the following is a specification:

My invention relates to improvements in burners, of the compressed-air type, for feeding oil to the flames in oil-burning furnaces for drop-forging and analogous purposes, and resides more particularly in the outlet and control therefor of the burner, the same being of certain peculiar construction, as hereinafter set forth.

The objects of my invention are, first, to provide a burner, of the class above indicated, which is capable of atomizing to the best advantage the fuel forced therethrough to be burned upon leaving the same, so that there shall be produced a more uniform heat, from less fuel, than is the case with most if not all other kinds of burners for a similar purpose; second, to do away entirely with the breaker-brick commonly employed, and which, as is well known, is a source of much trouble and is really an element of weakness, uncertainty, and inefficiency wherever present, and, third to provide a durable oil burner which is comparatively inexpensive and simple in construction, and enhances combustion so that practically no smoke is produced, the fuel all being consumed.

It follows that the burner must be economical in use, and it is true, furthermore, that with it combustion is obtained which approaches perfection.

I attain the objects and secure the advantages, herein pointed out, by the means illustrated in the accompanying drawings, in which—

Figure 1 is an elevation in partial section of an oil burner that embodies a practical form of my invention; Fig. 2, an inner end elevation of the valve shown in the preceding view, and, Fig. 3, a section of the outlet of a burner and the control therefor which embody slight modifications.

Similar figures refer to similar parts throughout the several views.

In order to obtain the best results from a burner of this kind, it is necessary to break up or atomize the fuel to a degree of fineness not easy of accomplishment heretofore, but with my burner I am able to

atomize the fuel to any degree of fineness. That I am able to do this is due to the peculiar construction of the valve which regulates the escape of fuel from the burner, 60 and which is a conical stepped valve, that is, it is provided with external annular flanges or shoulders of diameters which vary in regular gradation. A suitable valve-seat must, of course, be provided for the afore- 65 said conical stepped valve.

To still further enhance the atomizing process, the inner face of the valve may be sunken, dished, or concaved, so as to present a concave instead of a flat surface to the 70 fuel and with such surface or face commence the breaking-up process.

Passing now to the consideration in detail of the burner illustrated in the first view, it will be observed that such burner 75 comprises a casing 1 in which is a compressed-air chamber 2, a casing 3 in which is a mixing chamber 4, an oil tip 5, a valve 6, and a valve-stem 7 provided with a handle 8. The casing 3 is attached to the 80 casing 1 and the chambers in said casings open into each other.

Compressed air is furnished to the chamber 2 from any suitable source of supply. Oil is supplied to the chamber 4 from any 85 suitable source by way of the tip 5 which is tapped into the casing 3 and located so as to position its discharge end adjacent to the longitudinal center of said chamber.

The handle 8 is at one end of the valve- 90 stem 7 outside of the casing 1, and the valve 6 is at the other end of said valve-stem. The valve-stem 7 is screw-threaded at both terminals and the terminal which carries the handle 8 is tapped into the casing 1, so that 95 as said valve-stem is turned by means of said handle said stem moves longitudinally with the valve 6 to seat or unseat the same according to the directions of rotation and travel of the valve-stem. The valve terminal 100 of the stem 7 is slidingly mounted in a center block 9 which is supported and adjusted by means of four (more or less) centering screws tapped into the sides of the casing 3, two of such screws appearing at 10-10. 105

The outer end of the valve 6 is the larger and from this end the diameter of said valve diminishes by regular gradation until the smaller inner end or face is reached. Said face is dished at 11 and from its center a 110 hub 12 projects to receive the valve-stem 7. A plurality of flanges, shoulders, or steps 13

encircle the valve 6 on the outside, said steps being by preference abrupt or approximately at right-angles to the axis of said valve, with the connecting or riser portions approximately parallel with said axis, excepting in the case noted below.

The casing 3 terminates at its free terminal in a valve-seat 14 corresponding on the inside to the valve 6, that is, said valve-seat 10 has steps 15, similar to the steps 13, which are adapted to be engaged or contacted with by said steps 13 when said valve is closed. The valve-seat 14 is left tapering at 16 outside of the outermost step 15, and the valve 15 6 has a beveled part 17 which coincides with the part 16, this part 17 being the exception referred to above. These tapering parts 16 and 17 come together, when the valve 6 is closed, as well as the steps 15 and 13, that is 20 to say, not only are the steps 13 forced against the steps 15, upon the closing of the valve, but the part 17 is forced against the part 16, with the result that an absolutely gas-tight joint is formed between the valve 25 and the valve-seat 14.

In practice, air and oil under pressure are admitted to the chambers 2 and 4, respectively, to come together and mix in the chamber 4, the valve 6 is actuated outwardly 30 by means of the valve-stem 7 to open said valve to whatever extent is required, and the mixed oil and air, which constitute the fuel for the burner, escape through the valve-seat 14. The fuel is ignited and burns upon 35 leaving the chamber 4 by way of the valve-seat 14, combustion occurring at and beyond the free end of the casing 3 and the large end of the valve 6. The amount of fuel fed to the flames is increased or decreased by 40 actuating the valve 6 out or in to enlarge or make smaller the space between said valve and the valve-seat 14. The valve 6 is illustrated in its wide-open position, a position which it will seldom if ever be made to assume.

The fuel is impelled forcibly against the dished face of the valve 6 where the breaking-up process begins, from that said fuel glances swiftly in a splayed condition 50 against the riser portion of one of the steps 15, from the latter it is driven against one of the steps 13, then against the riser portion of the next outer step 15, and so on, being buffeted from step to step and reduced 55 to finer and still finer spray at each shock of contact until finally the thoroughly atomized fuel emerges from around said valve at the outer or free open end of the valve-seat 14 to be consumed by fire. During this 60 process the air and oil become more thoroughly and completely mixed than they are in the chamber 4, which is another advantage accruing from the peculiar construction of my burner. Without the steps 13, at least, 65 the proper mixing and atomizing of the fuel

elements could not well be effected, as is obvious from the foregoing explanation.

When it is no longer desired to use the burner, the valve 6 is closed, and the oil and air supplies are shut off.

The dishing 11 may be omitted, as is done in the construction shown in Fig. 3 wherein the inner end or face of the valve 6 is made plain, such plain face being indicated at 18. In this view, also, the steps 15 are omitted from the valve-seat 14 which has a plain tapered surface 19. In this case the edges of the steps 13 and the part 17 are brought into contact with the surface 19 when the valve is closed, there being no valve-seat 80 steps for said steps 13 to butt against as in the other case. These and other modifications that may fairly be said to fall within the scope of my claims are included in my invention.

The operations of or the results produced by the construction shown in the last view are very similar to those of or produced by the construction shown in the first view, and in a measure are as effectual or efficient, 90 although in a measure only, since the highest efficiency is found in the burner first shown and described herein.

What I claim as my invention, and desire to secure by Letters Patent, is—

1. The combination, in an oil burner, with a suitable casing having a valve-seat the diameter of which increases from within outward, of a conical valve arranged in operative relation to said valve-seat and provided with a plurality of concentric steps adapted to contact with said valve-seat when said valve is closed, and means to operate said valve.

2. The combination, in an oil burner, with a suitable casing having a valve-seat the diameter of which increases from within outward, of a conical concentrically stepped valve arranged in operative relation to said valve-seat and having a depressed face at its 110 inner end, and means to operate said valve.

3. The combination, in an oil burner, with a suitable casing having a concentrically stepped valve-seat which is largest at its outer terminal, of a conical concentrically 115 stepped valve arranged in operative relation to said valve-seat, and means to operate said valve.

4. The combination, in an oil burner, with a casing having a concentrically stepped valve-seat which is largest at its outer terminal, of a conical concentrically stepped valve arranged in operative relation to said valve-seat and having a depressed face at its inner end, and means to operate said valve.

5. The combination, in an oil burner, with a casing having a valve-seat the diameter of which increases from within outward, of a conical valve arranged in operative relation to said valve-seat, said valve being tapered 130

at its outer terminal to fit the corresponding part of said seat, and being provided with a plurality of concentric steps adapted to contact with said seat, when said valve is closed, and means to operate said valve.

6. The combination, in an oil burner, with a casing having a tapered and concentrically stepped valve-seat which is largest at its outer terminal, of a tapered and concentrically-stepped valve arranged in operative relation to said valve-seat, and means to operate said valve.

7. An oil burner comprising a mixing-chamber casing having a valve-seat at one end, the diameter of which valve-seat increases from within outward, an air-chamber casing at the opposite end of said first-mentioned casing, an oil inlet to the mixing-chamber between the air-chamber and the valve-seat, a conical concentrically stepped valve arranged in operative relation to said valve-seat and adapted to have its steps

brought into contact therewith when said valve is closed, and a stem for said valve, which stem extends through the mixing-chamber and the air-chamber and is tapped into the air-chamber casing.

8. An oil burner comprising an air-chamber casing, a mixing-chamber casing having a valve-seat the diameter of which increases from within outwardly, an oil inlet to said last-mentioned casing, a conical concentrically stepped valve arranged in operative relation to said valve-seat, a valve-stem for said valve, said valve-stem having its outer terminal tapped into said first-mentioned casing, a center block for the valve terminal of said stem, and centering screws tapped into said mixing-chamber casing for said block.
